Patented July 20, 1915.

UNITED STATES PATENT OFFICE.

HENRY HAMMONS AND ERASmus M. BLACKSHER, OF BREWTON, ALABAMA.

COMBINATION CEMENT TIE AND RAIL-CLAMPING MEANS.

1,147,321.

Specification of Letters Patent. Patented July 20, 1915.

Application filed January 25, 1915. Serial No. 4,186.

To all whom it may concern:

Be it known that we, HENRY HAMMONS and ERASmus M. BLACKSHER, citizens of the United States, residing at Brewton, in the county of Escambia and State of Alabama, have invented a new and useful Combination Cement Tie and Rail-Clamping Means; and we do hereby declare the following to be a full, clear, and exact description of the invention, such as will enable others skilled in the art to which it appertains to make and use the same.

This invention relates to an improved combination reinforced cement tie including improved clamping means for the rail carried by the reinforcing means.

As an object of the invention it is the aim to provide an improved device of this nature comprising a cement body having a U-shaped metallic bar embedded therein, together with embedded rods for reinforcing the cement structure.

Another object of the invention is to provide the reinforcing U-shaped bar with a tie plate, which may be either integrally cast with the bar or detachably connected, however, preferably integrally.

Another object of the invention is to construct an elongated slot in the tie plate to receive the shanks of the bolts, which fasten the rail clamping plate in place, there being a hollow portion below the tie plate to receive the heads of the rail clamping bolt.

In practical fields the details of construction may necessitate alterations, falling within the scope of what is claimed.

The invention comprises further features and combination of parts, as hereinafter set forth, shown in the drawings and claimed.

In the drawings, Figure 1 is a view in perspective of the improved cement reinforced tie constructed in accordance with the invention. Fig. 2 is a longitudinal sectional view through one end of the tie. Fig. 3 is a sectional view on line 3—3 of Fig. 2. Fig. 4 is a sectional view on line 4—4 of Fig. 2. Fig. 5 is a transverse sectional view, showing the tie plate made separate from the reinforcing bar, the same being fastened by a screw at each end of the tie plate, however, only one screw being shown. Fig. 6 is a detail view of a portion of the reinforcing bar, showing the tie plate as detached therefrom. Fig. 7 is a detail view of the tie plate.

Referring more particularly to the drawings, 1 designates the cement tie as a whole,

which comprises an elongated body having embedded therein U-shaped metallic bar 2, the opposite sides 3 of which are provided with lateral flanges 4 and 5 acting to hold the cement structure together, the cement of which also extends up between the opposite side portions of the metallic reinforcing bar, as shown at 6. To further reinforce the cement structure auxiliary reinforcing rods 7 are embedded therein, extending longitudinally of the tie. Each end of the U-shaped bar is constructed with a raised portion 8 cast integrally with which is a tie plate 9. Beneath each tie plate 9, the raised portion 10 is constructed with an elongated hollow 10, which is immediately below the elongated slot 11 of the plate. Adjoining the hollow 10 and positioned laterally thereof under the tie plate are recesses 13 substantially directly opposite each other, to receive the head 14 of the bolt 15, the shanks of which extend upwardly through the rail clamping plates 16, and are provided with nuts 17. Between the nuts 17 and the rail clamping plates 16 are coil springs 18, which are sufficiently compressed or tensioned by the nut 17, so as to hold the clamping plates 16 securely in place. However, owing to the construction of one side 19 of each aperture through which each bolt 15 passes, the rail clamping plates are allowed to yield a little. However, this yielding action is not so great that the rails 20 may spread far enough to permit improper contact or rolling of the car wheels on said rail, but just sufficiently to permit the rails to yield, incident to the wheels passing thereover, and then allow the rails to reset themselves. The rail clamping plates 16 are provided with recesses 21 on their under surfaces, to engage the base flanges of the rails. Each tie plate adjacent opposite sides of its elongated slot 11 substantially at the center portion of the slot is provided with cutaway portions or recesses 22, to permit the heads 14 of the bolts 15 to pass therethrough, when arranging the bolts, in such wise that their shanks may pass upwardly through the slot, as clearly shown in Figs. 2 and 3. To arrange each of the bolts 15 in position its head is passed through the opposite cutaway portions of recesses 22, so that its head may engage the recesses 13, and then by moving each bolt to a lateral position as shown in Fig. 2, its shank will extend vertically upward, so as to be passed through the rail clamping plate. After both rail

clamping plates are so arranged, the rail is then placed in its proper position, and subsequently the plates 16 are moved toward each rail, and the nuts 17 tightened sufficiently against said coil springs 18.

In Figs. 6 and 7 it will be observed that the tie plate may be made separate from the raised portion 8 of the reinforcing U-shaped bar. Therefore, in this case the tie 10 plate is secured in place by screw bolts 24, one at each end of the tie plate. To avoid further illustration only one of said screw bolts is shown.

From the foregoing it will be observed 15 that the reinforcing U-shaped bar bridges from one rail to the other, and constitutes means to withstand all lateral and longitudinal strains and weight incident to the rolling stock passing over the rails. In constructing the reinforced cement tie for practical use, it has been found practical as well as preferable to construct the tie plate as an integral part of the reinforcing bar, thereby not only insuring that all the strains 20 are carried by the bar, but also to avoid rattling and preventing the cement from cracking or crumbling. To further reinforce the cement body, each tie plate upon its under surface adjacent both ends thereof 25 and upon opposite sides of the U-shaped reinforcing bar, is provided with downwardly extending angular members or projections 30 as shown clearly in Figs. 3 and 4.

As shown in dotted lines in Fig. 2, it will 35 be noted that each end of the elongated reinforcing rods 7 is provided with an angular end 7^a, to further reinforce the concrete structure. Jam nuts 27 are threaded upon the shanks of the bolts 15 to lock the nuts 17 40 in place. After arranging the bolts 15 in their proper places, with their shanks passing upwardly through the rail clamping plates, wedges 28 are temporarily used to engage between the rail clamping plates and 45 the ends of the elongated slot 11, thereby acting to force the rail clamping plates firmly in contact with the rail. However, after the nuts 17 and the jam nuts 27 have been sufficiently tightened, to prevent un- 50 movement of the plates 16 in lateral directions, that is, away from the rail, said wedges are removed, after which each end of the slot 11 and the recesses 13 and the hollow 10 are filled with cement. To remove 55 the clamping plate 16 the nuts 17 and 27 are first removed, and then the coil springs, after which the rail may be lifted or raised, at the same time removing the clamping

plate 16 off the shanks of the bolt. To remove the bolts 15, it is only necessary to 60 move the bolts toward the opposite recesses 22, and then extract them. In this case new bolts may be inserted in a like manner.

The invention having been set forth, what is claimed as new and useful is:—

1. In combination with a cement tie body, a reinforcing core therefor comprising a U-shaped metallic bar having an elongated tie plate adjacent each end upon the upper portion, said tie plate having an elongated slot 70 to receive the shanks of rail clamping plate members, said U-shaped bar having an elongated hollow to receive the heads of said members, each slot having means to permit the members to be arranged in said slot. 75

2. In combination with a cement tie body, a reinforcing core therefor comprising a metallic U-shaped bar having at each end a raised part, each raised part being provided with a tie plate having an elongated slot, 80 said raised part having elongated recesses adjoining the slot to receive the heads of holding members of rail clamping plates, said holding members passing upwardly through the slot, the opposite walls of the 85 slot adjacent its central portion being formed with recesses oppositely disposed to receive the heads of the holding member when arranging them in the slot.

3. In combination with a cement tie body, 90 a reinforcing core therefor comprising a metallic U-shaped bar having at each end a raised part, each raised part being provided with a tie plate having an elongated slot, 95 said raised part having elongated recesses adjoining the slot to receive the heads of holding members of rail clamping plates, said holding members passing upwardly through the slot, the opposite walls of the slot adjacent its central portion being 100 formed with recesses oppositely disposed to receive the heads of the holding members when arranging them in the slot, said tie plate having downwardly extending angular projections at both ends and upon opposite sides of the bar to assist in reinforcing the cement structure, and auxiliary reinforcing tie rods in the cement body. 105

In testimony whereof we have signed our names to this specification in the presence of 110 two subscribing witnesses.

HENRY HAMMONS.
